Inventor:
Wm Hardman
By John W. Hardman Atty.

UNITED STATES PATENT OFFICE.

WILLIAM HARDMAN, OF HAMILTON, ONTARIO, CANADA.

EVENER-MOTION-CONTROLLED COMBINED DRIVE BETWEEN FINISHING LAPPER AND HOPPER FEEDER.

Application filed October 20, 1926. Serial No. 142,985.

My invention relates to improvements in evener motion controlled combined drives between finishing lapper and hopper feeder and the object of the invention is to devise 5 improved means whereby the automatic feed of the cotton or cotton waste to the finishing lapper from the hopper feeder is more uniformly controlled, thus resulting in a better, finished lap.

10 A further object is to bring the hopper feeder and finishing lapper with their drives into a single unit actuated by a single main drive.

15 In my United States Patent No. 1,595,466, dated August 10th, 1926, for a system of lapping cotton, I described and illustrated means for feeding loose cotton or cotton waste to the finishing lapper. The present invention presents an improved drive between the finishing lapper and the hopper feeder for achieving this result.

20 My invention consists of a combined drive between the finishing lapper and the hopper feeder constructed and arranged all as hereinafter more particularly described and illustrated in the accompanying drawing in which:—

25 Fig. 1 represents a side elevation of my apparatus including the hopper feeder and finishing lapper viewed from one side.

30 Fig. 2 is a similar elevational view from the other side, and

Fig. 3 is a plan view.

35 Like characters of reference indicate corresponding parts in the different views.

1 is the finishing lapper. 2 is the finishing lapper beater. 3 (Fig. 3) is the finishing lapper beater feed roller. 4 is the hopper feeder and 5 is its drive shaft for driving the spiked 40 lattice conveyor (not shown) in the hopper feeder.

45 6 is the main drive belt for the finishing lapper on the pulley 7 secured to the counter shaft 8 which also carries the pulley 9 which is connected by the belt 10 with the pulley 11 on the finishing lapper beater shaft 12. A second pulley 13 on the shaft 12 is connected by a belt 14 with the evener motion drive pulley 15 on the shaft 16. The shaft 50 16 also carries the bevel wheel 17 meshing with the bevel wheel 18 on the longitudinally extending side shaft 19 which carries at its rear end the bevel pinion 20 which meshes with the bevel wheel 21 on the verti-

cal evener motion pulley shaft 22. 23 is a 55 conical pulley thereon connected by a suitable belt 24 with the opposed conical pulley 25 on the stub shaft 26. 27 is a shifter extending around the belt 24 and actuated by the piano action elements in the hopper 60 feeder (not shown) to shift the belt 24 to control the speed of the finishing lapper beater feed roller 3.

The stub shaft 26 carries the worm 28 which meshes with a worm wheel 29 which through the medium of the clutch 30 drives the suitably journaled pinion 31 which meshes with the gear 32 on the beater feed roller shaft 33.

So far all the above parts and their arrangement to drive the feed roller 3 are standard. Hitherto the shaft 5 was driven by a belt from the feed roller shaft 33 through the medium of a dog clutch. I will now describe the standard control for throwing the above drive into and out of action. A control rod 34 is provided and adapted to be actuated by means on the finishing lapper so that it will be moved to throw out the dog clutch referred to as well as the clutch 30 when the lap on the finishing lapper is complete, the actuation of the clutch 30 being effected by a transverse rod 35 (Fig. 3). Thus when the finished lap is complete the feed roller 3 and the hopper feeder spiked 55 lattice are stopped.

It has been necessary to describe the above standard drive for feed roller and spiked lattice as my improved drive is connected thereto and dependent thereon. I will now 90 describe the improvements I have embodied.

To the upper end of the stub shaft 26 I have secured a bevel gear 36 which meshes with a bevel gear 37 on a suitably journaled transverse shaft 38, said shaft 38 having 95 thereon the free cotton conveying and condensing roller 39, and also having the pulley 40 secured to such shaft at the opposite end to the bevel gear 37. The pulley 40 is connected by the belt 41 with a pulley 42 free 100 on the shaft 5, said pulley 42 being also provided with the female element 43 of a friction clutch which has its male member 44 slidably secured to the shaft 5. The movement of the male member 44 is controlled by a lever mechanism 45 pivotally connected to the rod 34.

46 is a second transverse cotton conveying

and condensing roller secured on the suitably journaled shaft 47, the feed roller 3, and the conveying and condensing rollers 39 and 46 being situated above the feed lattice conveyor 48 and in spaced relation thereto.

The shaft 47 carries a sprocket wheel 49 which is connected to the sprocket wheel 50 on a sleeved extension 51 of the roller 39 by the chain 52, and such shaft 47 also carries 10 the sprocket wheel 53 connected to a sprocket wheel 54 on the feed roller shaft 33 by means of the chain 55. Thus the rollers 46 and 39 are driven from the feed roller shaft 33. The provision of such rollers condenses the 15 cotton or cotton waste being fed from the hopper feeder 4 to the finishing lapper beater 2 and assists in the accurate conveying of such material resulting in the formation of a much more uniform lap than has hitherto 20 been possible. Also the provision of operating the spiked lattice conveyor drive shaft 5 from the shaft 38 permits of a single drive being employed with the result that it enables the hopper feeder and finishing lapper 25 to be driven as a single unit.

When the clutches 30, 43, and 44 are thrown out the rollers 39 and 46 are stopped and when thrown in they function in synchronism. Moreover, the variation in the 30 speed of the driven shaft 26 of the evener motion causes a corresponding variation in speed to the rollers 39 and 46, and to the spiked lattice of the hopper feeder. Thus the cotton or cotton waste fed from the 35 hopper feeder to the finishing lapper is effectively controlled so that any appreciable variation in weight or texture of the material in the finished lap is obviated. Thin spots in the laps are avoided by the use of 40 this drive and the drive itself is more positive and results in less slipping of the evener belt.

What I claim as my invention is—

1. In an evener motion controlled combined drive between finishing lapper and hopper feeder, the combination with the evener motion driven element, of means driven from the evener motion driven element for condensing the material fed from the hopper feeder to the finishing lapper and assisting in its positive conveyal.

2. In an evener motion controlled combined drive between finishing lapper and hopper feeder, the combination with the evener motion driven element, of means driven from the evener motion driven element for condensing the material fed from the hopper feeder to the finishing lapper and assisting in its positive conveyal, and 60 means driven from the evener motion driven element for driving the hopper feeder.

3. In an evener motion controlled combined drive between finishing lapper and hopper feeder, the combination with the 65 evener motion driven element, of means

driven from the evener motion driven element for condensing the material fed from the hopper feeder to the finishing lapper and assisting in its positive conveyal, and means driven from the evener motion driven element 70 for driving the hopper feeder, the drives of the material condensing and conveyal assisting means and the means for driving the hopper feeder being so arranged that corresponding variations in their speeds 75 are effected depending upon the speed of the evener motion driven element.

4. In an evener motion controlled combined drive between finishing lapper and hopper feeder, the combination with the evener motion driven element, the feeder hopper lattice drive shaft and the finishing lapper beater feed roller, of means for driving the feed roller from the evener motion driven element, means for driving the hopper feeder lattice shaft from the evener motion driven element, material condensing and conveyal assisting rollers, and means for driving them from the feed roller.

5. In an evener motion controlled combined drive between finishing lapper and hopper feeder, the combination with the evener motion driven element the feeder hopper lattice drive shaft and the finishing lapper beater feed roller, of driving gearing between the evener motion driven element, and the feed roller, driving gearing between the evener motion driven element and the hopper feeder lattice drive shaft, material condensing and conveyal assisting rollers between the hopper feeder outlet and the feed roller and driving gearing between the feed roller and the condensing and conveyal assisting rollers.

6. In an evener motion controlled combined drive between finishing lapper and hopper feeder, the combination with the evener motion driven element, the feeder hopper lattice drive shaft and the finishing lapper beater feed roller, of releasable gearing between the evener motion driven element and the feed roller, releasable driving gearing between the evener motion driven element and the hopper feeder lattice drive shaft, material condensing and conveyal assisting rollers between the hopper feeder outlet and the feed roller, and driving gearing between the feed roller and the condensing and conveyal assisting rollers.

7. In an evener motion controlled combined drive between finishing lapper and hopper feeder, the combination with the evener motion driven element, the feeder hopper lattice drive shaft and the finishing lapper beater feed roller, of driving gearing between the evener motion driven element and the feed roller, a transverse shaft, means for driving the transverse shaft from the evener motion driven element, releasable means for driving the hopper feed-

er lattice shaft from the transverse shaft, a material condensing and conveyal assisting roller freely mounted on the transverse shaft, a second suitably journalled material condensing and conveyal assisting roller between the first mentioned condensing roller and the feed roller, and means for driving both condensing rollers from the feed roller.

8. In an evener motion controlled combined drive between finishing lapper and hopper feeder, the combination with the hopper feeder lattice drive shaft and the evener motion driven element, of a transverse shaft, means for driving the transverse shaft from the evener motion driven element, a friction clutch on the hopper feeder lattice drive shaft, and means for driving

one of the friction clutch elements from the transverse shaft.

9. In an evener motion controlled combined drive between finishing lapper and hopper feeder, the combination with the finishing lapper beater feed roller and the evener motion driven element, of releasable driving gearing between the evener motion driven element and the feed roller, material condensing and conveyal assisting rollers between hopper feeder and the feed roller, and driving gearing between the feed roller and the material condensing and conveyal assisting rollers.

In testimony whereof I affix my signature.

WILLIAM HARDMAN.
